CLAIM

The ornamental design for a custom webcam security cover, as shown and described.

DESCRIPTION

FIG. 1 is a front perspective view of a custom webcam security cover, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, front perspective view thereof, shown in a used condition with a computer in broken lines.

The broken lines in the drawings depict portions of the custom webcam security cover that form no part of the claimed design.
